CIGARETTE-MAKING MACHINE

Joseph V. Reid and Paul Richer, Montreal, Quebec, Canada, assignors to Genin Trudeau & Cie Ltée, Montreal, Quebec, Canada

Application March 5, 1942, Serial No. 433,502

7 Claims. (Cl. 131—70)

This invention relates to improvements in hand operated cigarette-making machines, and the principal object is to provide a simple, rugged and comparatively inexpensive machine by means of which well formed cigarettes may be produced rapidly and without the exercise of any particular skill on the part of the operator.

Other objects, advantages and characteristic features of the invention will be apparent from the following detailed description taken in connection with the accompanying drawings, in which—

Fig. 1 is a top plan view of our improved machine as it appears with the movable carriage in its starting position and with the tobacco molding members of the carriage separated to receive a charge of tobacco therebetween.

Fig. 2 is a top plan view of the machine as it appears after the molding members have been brought together to press a charge of tobacco therebetween, the carriage being shown in its starting position.

Fig. 3 is a top plan view of the machine as it appears after the carriage has been moved to the left from the position shown in Figs. 1 and 2.

Fig. 4 is a front end elevation.

Fig. 5 is a rear end elevation.

Fig. 6 is a top plan view of the guide plate assembly on which the carriage is slidably mounted.

Fig. 7 is a side elevation of the assembly shown in Fig. 6.

Fig. 8 is a side elevation of the machine as it appears with one of the side plates removed.

Fig. 9 is a transverse sectional view taken along the line 9—9 of Fig. 1.

Fig. 10 is a transverse sectional view taken along the line 10—10 of Fig. 2.

Referring more particularly to the drawings, 5 designates a carriage slidably mounted on a flat horizontal guide plate 6, the ends of said plate being fastened by screws 7 to supports 8 and 8a rising from the end portions of a base 9.

Carriage 5 includes a top wall 10, and walls 11 and 12 and removable side walls 13 and 14. The end walls 11 and 12 are preferably integral with the top wall 10 and are provided, near their lower horizontal edges, with guide slots 11a and 12a through which guide plate 6 extends, the upper horizontal edges of said slots being recessed as indicated at 11b and 12b. The side walls 13 and 14 are each provided with inwardly directed lugs 15 which fit between the end walls 11 and 12 and are removably secured thereto by screws 16. The end walls 11 and 12 are joined together by upper

and lower fixed plates 18 and 19, the plate 18 being spaced below the top wall 10 and the plate 19 being spaced below plate 18. The top carriage wall 10 is provided with a longitudinally extending slot 20 which constitutes the filling opening of a tobacco molding chamber 21, the end walls of which are provided with openings 22 and 23. The bottom wall of chamber 21 is formed by a slideable plate 24 (Fig. 9) which rests on and is slideable laterally across the previously mentioned fixed plate 18. Plate 24 carries a movable molding member 25 which forms a movable side wall of the molding chamber 21. Member 25 is here shown as a metal bar which is fastened to plate 24 by screws 25a and is provided, at its inner side, with a lengthwise extending semi-circular cavity 26, said cavity being formed so as to provide member 25 with a cutting edge 25b which is adapted to cooperate with a cutting edge 20a provided along one side of the slot or filling opening 20. With the carriage 5 in the position shown in Fig. 1 the opposite side wall of molding chamber 21 is formed by a stationary molding member 27 which is semi-circular in cross section and is arranged with its concave side opposed to the semi-circular cavity 26 of the movable molding member 25. Member 27 extends through the end openings 22 and 23 of molding chamber 21 when carriage 5 is in the starting position shown in Fig. 1. A tubular portion 27a, provided at the left hand end of member 27, is tightly secured around the free end of a cylindrical rod or plunger 30 which extends above and in parallel relation to the upper surface of the guide plate 6, the opposite end of said rod or plunger being directed downwardly through an opening 6a in plate 6 and into a socket 3b provided in the support 8.

The slideable plate 24 is wider than its supporting plate 18 and is connected by a link 32 to the short arm 33 of a bell crank operating lever 34 which is pivoted to the carriage 5 as at 35. The long arm 34' of operating lever 34 works in a slot 36 provided in side wall 14. A tubular neck extension 38 is secured to the end wall 12 of the carriage in line with the front end opening 23 of the molding chamber 21. This neck extension is bevelled at its free end as shown in Fig. 1 and is provided, at one side, with a full length slot 38a. This neck extension is adapted to fit freely inside one end of a standard cigarette tube X.

During part of the travelling movement of the carriage 5 the paper cigarette tube X is clamped to the neck extension 38 by means of a pivotally mounted cam actuated clamp lever 40. This lever 40 comprises a U-shaped strip of metal which is

pivoted to the front end wall 12 of the carriage by means of bushing 42 and pivot screw 41. A clamping shoe 43, preferably made of rubber or some other soft resilient material, is secured in place between the side portions of the lever 40 adjacent the free end of the lever and is adapted to be pressed against the neck extension encircling end of the cigarette paper tube X when the free end of the lever is swung upwardly by engagement of the lever with a cam plate 44 which is supported on and extends longitudinally of the guide plate 6, said cam plate 44 being provided with inclined end portions 45a and 45b and being of uniform height between said inclined end portions.

The pivotal connection between the slideable plate 24 and link 32 comprises a pivot screw 46, the shank of which is passed through the link opening 32a and through a threaded opening in plate 24. Washers 47 are interposed between the head 46a of screw 46 and the lower side of link 32 and a bushing 48 is interposed between the upper side of link 32 and the lower side of plate 24. The head 46a of screw 46 cooperates, as hereinabove described, with a locking bar 49 which is arranged on and extends longitudinally of the guide plate 6, it being noted that the locking bar 49 and the previously mentioned cam plate 44 are arranged so that they pass through the recesses 11b and 12b of the carriage guide slots 11a and 12a during movement of the carriage along the guide plate 6.

The link 32 is connected to the short arm 33 of bell crank lever 34 by a suitable pivot screw connection 50. The pivotal connection 35 between lever 34 and carriage 5 comprises a pivot screw 51 which is passed upwardly through an opening in plate 19 and is screwed into a threaded opening in plate 18. The portion of the screw 51 lying between the plates 18 and 19 is surrounded by a bushing 52 which is fitted in an opening provided in lever 34 and serves as a pivot bearing for said lever. A longitudinally extending angle iron 55 is secured to the lower side of the top wall of the carriage so that said angle iron forms a fixed side wall of the molding chamber 21 which lies at the side of the filling opening 20 remote from the removable molding member 25. A slight clearance is left between the angle iron or wall 55 and the upper surface of plate 18 to provide for the passage of slide plate 24. This angle iron acts as a back support for molding member 27 and prevents damage to said member if excess tobacco is compressed into chamber 21.

The machine described herein is used in the following manner: The carriage 5 is initially positioned as shown in Fig. 1 with the movable molding member 25 in a retracted position in relation to the fixed molding member 27. It will be noted that, in this position of the parts, the head of the pivot screw 46 is positioned against the front end of the locking bar 49 (Fig. 9) and therefore serves as a stop which prevents the carriage being moved to the left while the molding members are in their separated relation. A charge of loose tobacco is evenly distributed into the molding chamber 21 through the filling opening 20 and a cigarette tube X is fitted onto the neck extension 38. The long arm of lever 34 is then swung from the position shown in Fig. 1 to the position shown in Fig. 2 to effect movement of the slide plate 24 and the movable molding member 25 to the positions shown in Figs. 2 and 10. The movable molding member 25 is thus moved against the stationary member 27 to com-

press the interposed charge of tobacco into a solid cylindrical mass (Fig. 10), the surplus tobacco being sheared off by the cutting edges 20a and 25b as the movable molding member 25 travels across and closes the filling opening 20.

With the parts in the position shown in Figs. 2 and 10 it will be noted that the head 46a of screw 46 has been shifted to one side of locking bar 49 so that the carriage 5 is now free to be moved from the position shown in Fig. 2 to the position shown in Fig. 3. As the carriage commences this movement the clamp lever 40 rides up the inclined front end 45a of the cam plate 44 and causes the shoe 43 to be pressed tightly against the portion of the cigarette tube which is fitted on the neck extension 38. This clamps the cigarette tube on the neck extension 38 so that the tube is drawn over the cylinder of tobacco which is held against longitudinal movement by the right hand end 30a of the plunger 30.

The carriage 5 may be moved to the left until it strikes the support 8 but before the carriage reaches this position the clamp lever 40 reaches the rear inclined end 45b of the cam track 44 and drops down to release the clamping pressure on the cigarette tube X. At this exact point in the cycle of operations the friction between the tobacco and the inner wall of the cigarette tube holds the unclamped tube from any further movement with the consequent result that the neck extension is pulled clear from between the tobacco charge and inner wall of the paper tube. This extrusion and stripping action is complete when the carriage 5 has been moved until it strikes the support 8. The second half of the operating cycle is used to obtain two results: (1) to strip off the completed cigarette from semi-circular member 27, this being accomplished when the right hand end of extension 38 engages the free mass of tobacco which extends from the inner end of the paper tube. To provide this the cylinder of tobacco was designed nearly $\frac{3}{4}$ " longer than the tube; and (2) to return the carriage 5 to original position for refilling so that the two-way cycle may be repeated. When the carriage 5 is in the position shown in Figs. 3 and 10, the head 46a of the screw 46 is engaged with one side of the locking bar 49 and prevents retraction of molding member 25 until the carriage is returned to its original starting position where, as shown in Fig. 8, the head 46a of the screw 46 is positioned in advance of the front end of the locking bar 49 and is thus free to move across the guide plate 6 to permit the molding member 25 to be operated to its retracted position by swinging movement of the lever 34.

The molding member 27 is preferably punched to provide projections 27c to prevent slippage between this member and the tobacco during the tobacco molding and cigarette forming operations. Not only do these projections prevent slippage but also prevent any appreciable shortening in length or longitudinal compression of the cylinder of tobacco which would result in difficulty in operating carriage laterally.

Having thus described what we now consider to be the preferred embodiment of this invention it will be understood that various modifications may be resorted to within the scope and spirit of the appended claims.

Having thus described our invention, what we claim is:

1. A cigarette-making machine comprising a travelling carriage provided with a tobacco molding chamber having front and rear end openings

and a top filling opening, a guide along which the carriage is movable from a tobacco receiving and molding position at one end of the guide to a cigarette-forming position at or adjacent the opposite end of the guide, a stationary plunger and a stationary molding member secured together in alignment so that the molding member extends through the end openings and molding chamber of the carriage when the latter is in its tobacco receiving and molding position, and is replaced by the plunger when the carriage is shifted to its cigarette-forming position, a movable molding member arranged in said chamber and presenting a semi-circular molding surface which is opposed to a similar surface of the stationary molding member when said carriage is in said tobacco receiving and molding position, means for moving said movable member toward said stationary member whereby tobacco, previously interposed between said molding members, is compressed into a substantially cylindrical mass, and means for releasably holding a paper cigarette tube to said carriage so that said tube is aligned with the front end opening of the carriage, the arrangement being such that, when the carriage is moved to its cigarette forming position subsequent to the molding of the tobacco within said molding chamber, the fixed molding member passes out of the molding chamber through the front end opening and is replaced by the plunger, the lead end of which prevents any lateral movement of the cylinder of tobacco while the tube is being drawn over said cylinder as the carriage is moved from its initial position to the end of the first half of the operating cycle.

2. A cigarette-making machine as set forth in claim 1, in which the means for holding the paper cigarette tube to the carriage comprises a cylindrical neck extension surrounding the front end opening of the molding chamber and adapted to receive thereon one end of the cigarette tube and means for clamping said cigarette tube to said neck extension during the time that the carriage is being drawn over said plunger.

3. A cigarette-making machine as set forth in claim 1, in which the means for moving said movable molding member relative to said stationary member is operative only when the carriage is in its tobacco receiving and molding position, said means being locked against operation in all other positions of the carriage.

4. A cigarette-making machine as set forth in claim 1, including means whereby said carriage is locked in its tobacco receiving and molding position until said movable molding member is moved toward said stationary member, the locking means thereupon permitting said carriage to be shifted to its cigarette-forming position but preventing retraction of said movable molding member until the carriage is again returned to its cigarette receiving and molding position.

5. A cigarette-making machine as set forth in claim 1, in which the means for moving said movable molding member comprises a lever pivoted to said carriage and a link connection between said lever and said movable molding member.

6. A cigarette-making machine as set forth in claim 1, in which the means for holding the paper cigarette tube to said carriage comprises a neck extension fitted into one end of said tube, a pivoted clamping lever adapted to be swung from an inoperative position out of contact with said paper tube to an operative position in which

5 said clamping lever exerts clamping pressure against the portion of the tube encircling said neck extension and a cam track carried by said guide and arranged so that the clamping lever is engaged by said cam track and raised into clamping engagement with said tube when the carriage is moving through that portion of its travel during which the molding chamber passes over the tobacco cylinder dragging with it the 10 said tube until the latter becomes centralized over the cylindrical mass of tobacco.

7. A cigarette-making machine comprising a travelling carriage provided with a tobacco molding chamber having front and rear end openings and a top filling opening, a guide plate along 15 which the carriage is movable from a tobacco receiving and molding position at one end of the guide to a cigarette-forming position at or adjacent the opposite end of the guide, a locking bar and a cam track arranged on said guide plate, a stationary plunger and a stationary molding member secured together in alignment so that the molding member extends through the end openings and the molding chamber of the carriage when the latter is in its tobacco receiving 20 and molding position, said molding member being replaced by the plunger when the carriage is shifted to its cigarette forming position, a movable molding member arranged in said chamber and presenting a semi-circular molding surface which is opposed to a similar surface of the stationary molding member when said carriage is in said tobacco receiving and molding position, a bell crank lever pivoted to said carriage, connecting means securing said lever to said movable molding member whereby said movable molding member is moved toward said stationary molding member when the lever is swung in one direction and is retracted from said stationary molding member when the lever is swung in the opposite direction, the connection between said lever and said movable molding member including a part which cooperates with said locking bar to prevent movement of the movable molding member toward or away from the stationary molding member except when said carriage is in its tobacco receiving and molding position, the aforesaid end of said connection also serving to cooperate with said locking bar to prevent retraction of said movable molding member from said stationary molding member when the carriage has been shifted from its tobacco receiving and molding position after advancement of the movable molding member toward the stationary molding member, the arrangement being such that tobacco introduced into said chamber when the carriage is in its tobacco receiving and molding position is molded into a cylindrical mass by operating said lever to move the movable molding member toward the stationary molding member, the aforesaid part of the connection between the lever and the movable molding member being thus shifted relatively to said locking bar to permit shifting of the carriage from the tobacco receiving and molding position to the cigarette forming position, the aforesaid part of said connection between the lever and the movable molding member then cooperating with said locking bar to prevent retraction of the movable molding member until the carriage is returned to its tobacco receiving and molding position.
